(57) **CLAIM**

The ornamental design for a marine loading arm, as shown and described.

DESCRIPTION

1. Marine loading arm for transfer of fluids

1.1 : Left

1.2 : Left

1.3 : Perspective

1.4 : Perspective

1.5 : Back

The present design relates to a marine loading arm for the transfer of fluids; in the figures, the loading arm is shown in various configurations, i.e. mutual positions of the arms.
